UNITED STATES PATENT OFFICE.

WILLIAM EVERETT WHITESIDE, OF MIDWAY, WEST VIRGINIA.

CAR-COUPING.

SPECIFICATION forming part of Letters Patent No. 544,604, dated August 13, 1895.

Application filed February 28, 1895. Serial No. 540,116. (No model.)

To all whom it may concern:

Be it known that I, WILLIAM EVERETT WHITESIDE, of Midway, county of Putnam, State of West Virginia, have invented certain new and useful Improvements in Car-Couplers, of which the following is a specification, reference being had to the accompanying drawings.

The object of my invention is to produce a coupling device for railway-cars of the variety known as "twin couplers," whereby the cars are automatically coupled, and may be uncoupled from the side or top of the car without the necessity of the operator being subjected to the danger of being crushed between the cars.

In the accompanying drawings, Figure 1 is a perspective view of the lower front edge of a car with my car-coupler attached thereto. Fig. 2 is a horizontal sectional view of the draw-head. Fig. 3 is a longitudinal vertical section on line 3 3 of Fig. 1. Fig. 4 is a similar view on line 4 4 of Fig. 1. Fig. 5 is a vertical transverse view on line 5 5 of Fig. 3.

Referring to the figures on the drawings, 1 indicates a car-body having secured to its bottom, as by bolts 2, a draw-head 3, provided with a medial wall 4, defining parallel casings 5 and 6.

7 indicates a link-bar carried within the casing 5 by a revolvably-mounted transverse shaft 7, upon which it is pivoted, as by a vertical bolt 8. It will be seen that by this construction the link-bar is vertically and horizontally movable, movement in either direction being opposed by springs 9, bearing, respectively, against noses 10 upon the four sides of the link-bar and behind the revolvable shaft. I prefer to employ ordinary flat springs secured within the casing, as illustrated; but it is obvious that various other forms might be employed, the object being to return the link to its normal position after unusual strain in any direction is relieved.

Upon the outer end of the link-bar and projecting in front of the draw-head I provide a longitudinally-adjustable link 12, adjustable upon the link-bar by any suitable means—such, for instance, as a slot 13 in the bar through which the end of the link is adapted to pass, and by a prong-key 14 passed through

two of a number of graduated apertures in the bar and straddling the end of the link.

The mechanism described constitutes what I will call the "link side" of my coupler, and I shall now describe the mechanism, which operates with a similar link side upon another car to couple the cars together.

15 indicates an aperture in the top of the casing 6, across which a longitudinal guide-bar 16, that plays within a slot 17 in the pin 18, is secured.

19 indicates a shaft, mounted in suitable bearings upon the top of the sill of the car, provided with a crank, bent, as indicated at 20, to form a depending support 21, to which the link is pivotally secured at its upper end, and with actuating-cranks 22 at its opposite ends, by means of which the link may be raised when it is desired to uncouple the cars.

In order to produce a coupler which can be practically operated and whereby the coupler may be set in such position that the operator need not manipulate any of the parts while the cars are being drawn apart, it is necessary to provide means for locking the pin in the elevated position, to accomplish which purpose I provide a pivoted latch 23, in operative proximity to one of the cranks 22 and urged in the proper direction to engage therewith, when the same is operated to elevate the pin, by a spring 24, and having an upwardly-extending handle 25.

26 indicates a latch-bar pivotally secured to the latch above its pivot and extending across to the opposite side of the car, where it is provided with a handle 27.

The operation of my device is as follows: Supposing that it is desired to couple cars provided with my improved coupler and the parts to be in the position indicated in Fig. 1, the link being in the depressed position, the link of the opposing car enters the casing 6 and, striking the pin, swings it until the end of the link has passed therebeyond, when, as will be seen, the pin will swing back to its normal position, its lower end passing through and beyond the link, thereby effecting the coupling of the parts. It is obvious that the yielding of the link in either direction will permit coupling of cars varying in the exact vertical or horizontal location of their oppos-

- ing couplers. The train having reached its destination and the uncoupling of the cars being desired, it is only necessary to raise either of the actuating-cranks, the pin being elevated out of engagement with the link and the parts being secured in that position by the latch. Whenever it suits the convenience of the operator the latch may be withdrawn from engagement with the actuating-crank from either side of the car through either the handle upon the latch or the connecting-bar, allowing the pin to drop into the proper position for a repetition of the coupling operation.
- 15 I do not desire to limit myself to the details of construction herein shown and described, but reserve to myself the right to modify and vary the same at will within the scope of my invention.
- 20 What I claim is—
1. The combination with a draw head, of an intermediately, horizontally and vertically pivoted bar, a longitudinally adjustable link secured to the forward extremity of the link bar, opposing springs secured within the draw head in operative proximity to the rear extremity of the link bar, substantially as specified.
  2. In a car-coupler, the combination with a draw head, of a horizontally and vertically pivoted link bar therein, diametrically opposite noses upon the rear extremity of the link bar behind its pivot, and a plurality of parallel springs secured at one extremity to the draw head behind the link bar and having their free extremities in operative proximity to the noses, substantially as specified.
  3. In a car coupler, the combination with a draw bar, of a pivoted spring actuated link bar provided with a slot and a series of aper-

tures on both sides thereof, a link passing through the slot, and prong keys engaging the apertures to retain the link in its adjusted positions, substantially as specified.

4. In a car coupler, the combination with an apertured draw bar provided with a longitudinal guide bar, of a slotted pin guided by said guide bar, and means for raising and lowering the pin, substantially as specified.

5. In a car coupler, the combination with a draw head and pin, of a crank bar provided with a crank bent to form a depending support for the pin, a spring latch co-operating with the crank bar, mechanism at both sides of the car for actuating the crank bar and latch, substantially as specified.

6. The combination with a draw-head, provided with a medial wall defining two casings, of a vertically and horizontally movable link bar in one casing held in its normal position by opposing springs, a link adjustably secured to said link bar, a pin in the other casing provided with a slot co-operating with a guide bar to guide said pin, a crank shaft provided with a crank loosely pivoted to the upper extremity of the pin above the draw-bar, actuating cranks upon the opposite ends of the crank shaft located at opposite sides of the car, a spring actuated latch adapted to engage one of the actuating cranks, and a latch bar pivotally connected to the latch and extending to the opposite side of the car, and handles upon the latch and latch-bar, substantially as set forth.

In testimony of all which I have hereunto subscribed my name.

WILLIAM EVERETT WHITESIDE.
